(57) **CLAIM**

The ornamental design for a display device, as shown and described.

DESCRIPTION

FIG. 1 is a perspective view of a display device showing our new design;

FIG. 2 is a front view for the display device shown in FIG. 1;

FIG. 3 is a rear view for the display device shown in FIG. 1;

FIG. 4 is a left side view for the display device shown in FIG. 1;

FIG. 5 is a right side view for the display device shown in FIG. 1;

FIG. 6 is a top view for the display device shown in FIG. 1; FIG. 7 is a bottom view for the display device shown in FIG. 1; and,

FIG. 8 is a perspective view of the display device of FIGS. 1-7 shown with additional environment.

The broken lines in the drawings are for the purpose of illustrating portions of the display device that form no part of the claimed design. The additional broken lines in FIG. 8 illustrate environment and form no part of the claimed design.

1 Claim, 8 Drawing Sheets
